US0D1015311S

(12) **United States Design Patent** (10) **Patent No.:** **US D1,015,311 S**
(45) **Date of Patent:** **** Feb. 20, 2024**

(54) **HOLDER FOR MUSIC ACCESSORIES**

(71) Applicant: **ACCESS PRODUCTS GROUP, LLC**,
Kingston, WA (US)

(72) Inventors: **Ryan Kallas**, Playa del Ray, CA (US);
J. Herschel Blankenship, Kingston,
WA (US)

(73) Assignee: **Music Express LLC**, Kingston, WA
(US)

(**) Term: **15 Years**

(21) Appl. No.: **29/740,945**

(22) Filed: **Jul. 8, 2020**

Related U.S. Application Data

(63) Continuation of application No. 29/623,444, filed on
Oct. 25, 2017, now Pat. No. Des. 890,142, and a
continuation of application No. 29/502,138, filed on
Sep. 12, 2014, now Pat. No. Des. 801,315, which is
a continuation of application No. 29/421,803, filed on
Sep. 26, 2012, now Pat. No. Des. 714,267.

(57) **CLAIM**

The ornamental design for holder for music accessories, as
shown and described.

DESCRIPTION

FIG. 1 is a front view of a holder for music accessories
showing the new design;

FIG. 2 is a back view of a holder for music accessories as
seen in FIG. 1;

FIG. 3 is a bottom side view of a holder for music accessories
as shown in FIG. 1;

FIG. 4 is a top view pivoted 90° from the front view of a
holder for music accessories as shown in FIG. 1;

FIG. 5 is a front perspective view of a holder for music
accessories as shown in FIG. 1;

FIG. 6 is a right side view of a holder for music accessories
as shown in FIG. 1; and,

FIG. 7 is a left side view of a holder for music accessories
as shown in FIG. 1.

The broken lines depict portions of the holder for music
accessories that form no part of the claimed design.

1 Claim, 7 Drawing Sheets
